UNITED STATES PATENT OFFICE.

CHRISTOPHER M. WYANT, OF EAST ST. LOUIS, ILLINOIS, ASSIGNOR OF ONE-HALF TO JOSEPH M. BOGGMANN, OF SAME PLACE.

EARTH-AUGER.

SPECIFICATION forming part of Letters Patent No. 554,968, dated February 18, 1896.

Application filed October 25, 1895. Serial No. 566,866. (No model.)

To all whom it may concern:

Be it known that I, CHRISTOPHER M. WYANT, of East St. Louis, St. Clair county, Illinois, have invented a certain new and useful Improvement in Earth-Augers, of which the following is a full, clear, and exact description, reference being had to the accompanying drawings, forming a part of this specification.

My invention relates to an earth-auger containing novel features that adapt it for operation in all qualities of earth and under the varying conditions of the ground, and forms an auger which is easily removed from the ground in withdrawing it for removal of the accumulated earth.

To this end my invention consists in a two-section bit having blades arranged with oppositely-presented angles and a downwardly-extending lip on each bit at opposite sides of the bit, a yoke connecting said bit-sections to the operating-stem, an upwardly-extending rim at the outer edge of each bit-section by which the auger cuts its way on removal from the ground, a downwardly-extending toothed rim provided with teeth that cut any roots or like obstructions with which the auger may come in contact, an adjustable center bit of non-circular form in cross-section that will enter the hardest ground to form a center in starting the auger into the ground; and my invention consists further in the details of construction hereinafter described and pointed out in the claims.

Referring to the drawings, Figure I is a side elevation of my improved auger. Fig. II is a top view with the stem shown in cross-section. Fig. III is a side elevation looking at the side instead of the ends of the bit-sections. Fig. IV illustrates the auger-stem in vertical section and the center bit in elevation. Fig. V is a view of the under side of the auger. Fig. VI is an inside edge view of one of the bit-sections. Fig. VII is a section taken on line VII VIII, Fig. V, through one of the bit-sections. Fig. VIII is a section taken on line VII VIII, Fig. V, illustrating the insertion of a washer between the yoke and bit for the purpose of canting the cutting end of the bit-sections. Fig. IX is a section taken on line IX IX, Fig. VI. Fig. X is a section taken on line X X, Fig. VI.

In the drawings, 1 designates the stem of the auger, which is made of tubing, such as gas-pipe, and may be provided with a handle to operate the auger manually, or may be actuated by suitable mechanical means, and the stem may be of sections detachably connected together. In the lower end of the stem is fitted a center bit 2 of non-circular form, preferably square in cross-section, which form causes it to readily bore into the ground to guide the auger in starting it. This center bit is held by a set-screw 3 in the stem 1, thereby permitting of the adjustment of the bit to the varying conditions of the ground, inasmuch as where the ground is hard it is necessary that the point project only a short distance below the auger, whereas in soft ground it can project a greater distance, as it will readily enter the soft ground before the auger-bits begin to operate. Another object in having the bit 2 removably attached is to permit of its removal to sharpen it or insert a new one when the one in use becomes dulled.

4 designates a yoke connected to the stem 1 and to which the bit-sections 5 are attached by screws 6 or other suitable fastenings. This yoke forms but little obstruction to the passage of dirt onto the auger, and therefore it is a material feature of construction in my auger.

Each of the bit-sections 5 has an inclined blade portion 7, the lower portions of which form cutting-lips 8 at which the blades taper from the upper surface, as illustrated in the section shown in Fig. IX, so that the blade will readily enter the ground, while at the elevated portions the edges of the blades taper from the under surface, as illustrated in Fig. X, in order that no obstruction will be presented on the reverse movement in withdrawal of the auger from the ground.

For the purpose of canting the cutting end of each bit and causing it to take a ranker cut into the ground, I may employ a washer 9, inserted between the yoke and the bit-section, (see Fig. VIII,) which lowers the bit at that end, as is clearly illustrated in said figure.

The bit-sections 5 are provided with vertical rims 10 on their outer upper edges, said rims being provided with cutting-edges 11 11^a, the purpose of said rims being to cut the ground

at the edge of the hole in the descent of the auger. This rim has a further use in removing the auger from the ground, which I will now recite. The operator of an earth-auger 5 in standing over the hole bored by the auger and drawing upward on the auger naturally exerts a considerable downward pressure on the ground on which he stands, and as a consequence the earth is pressed inward toward 10 the cavity, which renders it a difficult matter to remove the auger from the ground to discharge the accumulated dirt. The cutting-edge 11 cuts the way on the removal of the auger and facilitates an easier removal. Directly beneath the rims 10 are rims 12 on the 15 under side of the bit-sections, provided with teeth 13 that serve the double use of trimming the ground at the edge of the hole and also cut any roots or similar obstructions with 20 which they may come in contact in the process of boring.

I have described my auger in connection with earth-boring only, but it is evident it might be employed for boring in other substances, and therefore I do not limit myself 25 to its use for such purpose.

I claim as my invention—

1. In an earth-auger, the combination of an operating-stem, bit-sections carried by said stem, said bit-sections being provided with 30 inclined blade portions and toothed rims at the outer edges of their under surfaces, substantially as and for the purpose set forth.

2. In an earth-auger, the combination of an operating-stem, bit-sections carried by said stem, said bit-sections being provided with 35 rims at the outer edges of their upper surfaces, and toothed rims at the outer edges of their under surfaces, substantially as and for the purpose set forth.

3. In an earth-auger, the combination of an operating-stem, a yoke connected to said stem, an adjustable non-circular center bit carried by said stem, bit-sections carried by said yoke, said bit-sections being provided with rims at 40 the outer edges of their upper surfaces, and toothed rims at the outer edges of their under surfaces, substantially as and for the purpose set forth.

CHRISTOPHER M. WYANT.

In presence of—

E. S. KNIGHT,
N. FINLEY.
